UNITED STATES PATENT OFFICE

2,129,480

TUBULAR WATCHCASE

Herman Schlacht, Woodhaven, N. Y.

Application April 20, 1934, Serial No. 721,418

8 Claims. (Cl. 58—88)

My invention relates to tubular watch cases of the type described in my United States Letters Patent No. 1,891,611, issued December 20, 1932.

My invention has for its object to provide a construction which is cheaper to manufacture than that shown in the said patent and which will lend itself readily to being combined with a lighting mechanism, lip stick, pencil, etc. As described in the said patent, the movement is slid into the tube from one end.

In my present invention the principal object is to preferably form the case of a number of tubular sections or portions which may be telescoped into a tube or otherwise secured thereto to hold them securely in place. The movement is located in one of the tubular portions. In this construction the movement can be placed in one of the tubular portions, the others secured to or around it, or an enclosing tube may be slipped over the assembled parts holding them firmly in place.

Other objects will appear from the hereinafter contained description and claims.

My means of accomplishing the foregoing objects may be more readily understood by having reference to the accompanying drawings which are hereunto annexed and are a part of this specification, in which—

Fig. 1 is a front elevation of the case combined with a lighter showing the case closed;

Fig. 2 is a side elevation of the same;

Fig. 3 is a front elevation with the case opened and the lighter removed from the case;

Figs. 4, 5 and 6 are enlarged detail views of the same;

Fig. 7 is a cross section taken on the line 1—1 in Fig. 2;

Fig. 8 is a front elevation of a modified form combined with a lip stick, the case being closed;

Fig. 9 is a side elevation of the same;

Fig. 10 is a front elevation with the case open and the lip stick removed;

Figs. 11 to 16 are detail views of the various parts of this modified form;

Fig. 17 is a side elevation of a modified form, the case being closed;

Fig. 18 is a side elevation of the same;

Fig. 19 is a front view with the case opened;

Fig. 20 is a section taken on the line 20—20 in Fig. 17;

Fig. 21 shows a modified arrangement for the light mechanism;

Fig. 22 is an enlarged detail view of the upper part of the case shown in Fig. 20;

Figs. 23 and 24 are fragmentary views of a modified form;

Fig. 25 is an enlarged detail view in vertical section;

Fig. 26 is a cross section taken on the line 5 26—26 in Fig. 25; and

Fig. 27 is an enlarged detail view of the inner section of the form shown in Fig. 24.

Similar reference numerals refer to similar parts throughout the entire description. 10

As shown in the drawings, Figs. 1 to 7, the case is formed of tubular sections or portions 1, 2, 3 and 4. The section 1 contains a lighting mechanism 5. Section 2 is adapted to receive the projecting part of the lighting mechanism 5 while 15 the upper end is closed and has a threaded portion on to which is screwed section 3. The section 2 may be provided with the usual smoothed portion 2' to receive a monogram. As illustrated, it is rectangular but obviously it may be of any of 20 the shapes which are provided on articles of jewelry on which to engrave a monogram. This section 3 has a cut-away portion adapted to expose the face 6 of the watch movement. The upper end of the section 3 is closed by a disc 7 25 which extends outwardly over the cut-away portion, the disc 7 being of the same diameter as the tube out of which the section 3 is formed. Within the space formed by the cut-out portion 1 mount the section 4 which contains the watch 30 movement W as clearly seen in Fig. 4.

The ends of the section 4 are closed by discs 8 and 9 which are provided with central threaded apertures to receive screws 10 and 11. The tubing forming section 4 is of sufficiently small 35 diameter to rotate freely inside of the section 3. The central portion of section 4 is cut away and is fitted with a crystal 12 which covers the face of the movement. The remaining portion of the wall of section 4 which is in register with the crystal 12 comprises a knurled portion 13, the knurling being to facilitate the rotation of the section 4. It is obvious that when the knurled portion is presented, as shown in Fig. 1, that the crystal is protected by the rear wall of the 40 section 3.

It will be apparent from the foregoing description that all that is necessary to do if one desires to remove the movement is to take out the two screws 10 and 11, when the section 4 will drop 50 out of the section 3 and by removing the disc 8 easy access is afforded to the movement. Preferably the disc 9 is soldered in position though, if desired, it can be frictionally held, as is the disc 8. In Figs. 8 to 16 inclusive, I have shown 55

a modified form of construction in which the case is formed of three tubular sections or portions 20, 21 and 22. The section 20 as clearly seen in Fig. 10 comprises a container for a lip stick which 5 is of the common standard form and is adapted to telescope inside of the tubular section 21. This section 21 has a cut-out portion which exposes the face 23 of the movement. The movement is mounted in the tubular section 22 as clearly seen 10 in the detailed views. The upper end is closed by a disc 24 which closes the tube, the diameter of the disc 24 being the same as the outside diameter of the tube forming section 21. The lower end of the section 22 is preferably closed by 15 means of a flanged disc 25 to which is secured, preferably by means of a rivet 26, a flanged disc 27 which is of slightly larger diameter than the tube forming the section 22, the rear 28 of the section 22 being preferably knurled as clearly seen 20 in the detail views. This knurled portion may be, if desired, provided with the smoothed portion 21' similar to the corresponding portion 2' in the other views, and on which may be engraved a monogram if desired. That portion of the section 22, which covers the face 23 of the movement, is closed by a crystal 29.

A slot 30 is cut in the top of the section 21 to permit the passage of the crown stem 31 when the section 22 is being inserted into the section 21.

The result of this construction is that when the section 22 is telescoped in the section 21, the flanged disc 27 exerts sufficient frictional pressure against the wall of the tubular section 21 35 to hold the disc against rotation thereby permitting the section 22 to be freely rotated upon the pivot 26.

As shown in Figs. 17 to 20 inclusive, and in Fig. 22, the case is made up of tubular sections 40 30', 31', 32 and 33; as illustrated the section 30' is provided with lighting mechanism which is adapted to telescope the lower portion of the section 31'. In some instances it may be found desirable to reverse the position of this lighting 45 mechanism as shown in Fig. 21 and mount a pencil attachment 34 on it. The section 31' is adapted to telescope the shoulder 35 on the section 30' and to receive at its upper end the lower end of the section 32. This movement containing portion or section 32 comprising a tubular portion closed at its upper end and provided with a cut-away portion in which is mounted the crystal 36 opposite the face 37 of the movement. The section 32 has its rear wall cut away and a segmental section 38 is fitted thereto. A screw 38a having its head projecting slightly beyond the periphery of a plug 38b, which constitutes the top of the section 32, forms means for engaging a stop wire 38c, carried by and movable with the section 33, said wire sliding in a groove 38e formed vertically along the surface of 32. This stop prevents complete disengagement of the cover, constituted by section 33, from the section 32, in the normal operation of the cover. However, when necessary, such complete disengagement of the cover 33 may be effected by inserting a screwdriver through a hole 38d and removing screw 38a. Union of the sections 31' and 32 may be effected by screw 32a, which traverses 31' and 70 32 and takes into a block 32b, spanning the section 32.

A slot 39 is formed in the wall of the section 33 to permit the crown stem to pass therethrough. To look at the watch in this form of case one 75 slides the section 33 upwardly until the face 37

of the movement is exposed. By constructing the section 32 in the manner described it is obvious that I have materially cheapened the construction and made it possible to mount the movement with a minimum of expense. Monogram plates 5 31'' may be applied to or formed upon the sections 31', as indicated.

As shown in Figs. 23 to 27 inclusive I have provided a simple form of construction for the movement containing section. As shown in these 10 figures, the case comprises sections 40, 41 and 42. The section 41 contains the movement and has discs 43 and 44 closing the ends thereof. These discs are held in place by means of screws 45 and 46. This section is also provided with a 15 cut-out portion in which is mounted a suitable crystal 47 to expose the face of the movement. In this construction the section 41 is held against rotation by means of springs 48 and 49 which are preferably formed of piano wire and are fitted 20 to a groove 50 formed in the section 41. These springs provide sufficient frictional engagement to assist in preventing the sections 40 and 42 from sliding off of the section 41. A hole 51 is provided adjacent the top of the section 42 for the 25 insertion of a screwdriver to remove the screw 46. A similar hole 52 is provided in the section 40 in such a location that it will register with the screw 45 when it is desired to remove it. It will be apparent from the foregoing description that I have 30 provided an extremely inexpensive section for mounting the movement, the tubular portion 41 holding said movement being formed in halves which are held together by the telescoping tubular end sections 40 and 42.

Having described my invention what I regard as new and desire to secure by Letters Patent is—

1. In a sectional tubular case for watches, a plurality of tubular portions, one of which contains the movement; discs which close the ends of the movement containing portion, and screws mounted in said discs, said screws being rotatably mounted in one of said tubular portions. 40

2. In a sectional tubular case for watches, a plurality of tubular portions, one of which contains the movement; discs which close the ends of the movement containing portion, one section having a part of its wall cut out adjacent one end, there being a slot in the wall above said cut-out part, a flanged disc rotatably secured to one end of the movement containing portion, the diameter of said disc being slightly larger than the outside diameter of said portion, whereby when telescoped inside the section having the 55 cut-out portion it will be held against rotation.

3. In a sectional tubular case for watches, a plurality of tubular portions, one of which contains the movement; discs which close the ends of the movement containing portion, said movement containing portion being formed in sections which when assembled will telescope the other portions which hold the sections forming the movement containing portion in assembled relation. 60

4. In a sectional tubular case for watches, a plurality of tubular portions, one of which contains the movement; discs which close the ends of the movement containing portion, the movement containing portion being formed in halves 70 adapted to telescope the other portions, screws which hold said discs in place, there being a longitudinal groove in one of said halves, springs in the telescoped portions which slide in said groove, there being apertures in the said tele- 75

scoped portions adapted to register with said screws whereby they may be removed from the exterior of said sections.

5. In a sectional tubular case for watches, a plurality of tubular portions, one of which contains the movement; discs which close the ends of the movement containing portion, one section having a part of its wall cut out adjacent one end, there being a slot in the wall above said 10 cut-out part, a flanged disc rotatably secured to one end of the movement containing portion, the diameter of said disc being slightly larger than the outside diameter of said portion, whereby when telescoped inside the section having the 15 cut-out portion it will be held against rotation, a disc secured to the other end, the diameter of which is the same as the outside diameter of the tube having the cut-out portion.
6. In a sectional tubular case for watches, a plurality of tubular portions, one of which contains the movement; discs which close the ends of the movement containing portion, one section having a part of its wall cut out adjacent one end, there being a slot in the wall above said cut- 20 out part, friction means rotatably secured to said 25

movement containing portion, and which engages the walls of the section having the cut-out portion.

7. In combination, a casing comprising a plurality of aligned tubular sections adapted for engagement with one another, a watch movement mounted in one of said sections, a face for said movement, said sections arranged so that movement of one or more predetermined sections in one direction will cover the face of the watch 10 movement while movement in another direction will expose it, said watch movement comprising a winding crown projecting outwardly of the cover section.

8. In a sectional tubular case for watches, an outer tubular section having a cutaway portion to expose the watch face, an inner section which contains the movement located in said outer section, a disc fixedly mounted in the lower end of the movement containing section, a flanged disc 20 pivotably secured to the fixed disc, the flange of which frictionally engages the inside of said outer section, whereby the movement containing portion may be rotated.

HERMAN SCHLACHT. 25
